UNITED STATES PATENT OFFICE.

DAVID G. McCAA, OF LANCASTER, PENNSYLVANIA, ASSIGNOR TO THE ELECTRIC APPARATUS CO., OF PARKESBURG, PENNSYLVANIA, A CORPORATION OF PENNSYLVANIA.

RADIO SYSTEM.

Application filed June 25, 1924. Serial No. 722,246.

My invention relates to the reception of high or radio frequency energy, without interference or disturbance due to other high or radio frequency energy produced artificially or by natural electricity, as static, atmospherics, etc., in systems in which the energy is transmitted either through the natural media or over a conductor or conductors extending between transmitting and receiving stations, for purposes of effecting at receiving stations controls, or signals which may be either telegraphic or telephonic.

In accordance with my invention, the frequency of the energy which it is desired should be excluded or reduced in effect and represented by oscillations set up by static or other natural electricity is caused to be lower than the frequency of the energy which it is desired shall be received, and a signal-translating circuit, normally absorbing substantially no energy of either the desired or undesired oscillations, is caused to absorb energy of the desired oscillations and translate it into a control or signal in response to a change in the natural period of the path or circuit which absorbs the energy from the natural media.

Further in accordance with my invention, whatever be the relation of the frequencies of the desired and undesired oscillations, the signal-translating circuit is oppositely influenced through a plurality of inductive couplings with a circuit or path in which both the desired and undesired oscillations are present.

Further in accordance with my invention, the natural period of the circuit or path which absorbs the energy from the natural media includes inductances in parallel with each other and preferably of different magnitudes, the inductance of lesser magnitude preferably utilized for coupling to the signal-translating instrument and the larger inductance subjected to amplified received oscillations of signal or desired frequency to materially reduce the inductance of the parallel inductances and thereby change the natural frequency of the absorbing path or

circuit to approach or equal the frequency 50 of the desired oscillations or signal, and thereby causing the signal-translating instrument to absorb oscillations of desired frequency.

Further in accordance with my invention, 55 there is utilized for amplifying oscillations of the desired frequency a thermionic amplifying tube whose input circuit, resonant to the frequency of the desired oscillations and in which the tuning inductance preferably 60 greatly predominates over the tuning capacity, is coupled, either magnetically or capacitatively, to the absorbing circuit or path, and the coupling is preferably loose, and in any event controllable as to magnitude or degree, 65 whereby the input circuit becomes highly selective and excludes oscillations of undesired frequency, which may reach the input circuit through said coupling, and the input circuit also sharply rejects oscillations of 70 undesired frequency which may be impressed thereon through the grid to plate capacity of the tube; and the aforesaid capacitative or magnetic coupling opposes, as regards the input circuit, such coupling as 75 may obtain between the input and output circuits of the tube through the capacity between the grid and anode thereof.

Further in accordance with my invention, 80 there may be utilized with a capacitative coupling of the character above referred to means, such as a circuit tuned to the frequency of the undesired oscillations and a co-operating second capacitative coupling, for effecting a point of zero potential as regards the oscillations of the undesired frequency, and the first named capacitative coupling effects coupling with the absorbing path or circuit through such point of zero potential, whereby the input circuit of the 85 tube is further shielded from the influence of oscillations of undesired frequency.

Further in accordance with my invention, 90 there may be utilized in the capacitative coupling path between the absorbing circuit or path and the input circuit of the tube capacity and inductance in parallel and tuned to the frequency of the undesired oscilla-

tions, the inductance preferably greatly predominating over the capacity in such tuned or parallel resonant circuit; further in accordance with my invention, the output circuit of the amplifying tube may be reversely magnetically coupled to its input circuit to neutralize the coupling between input and output circuits as affected by the grid to anode capacity of the tube; and by preference, both the reverse magnetic coupling and the parallel resonant circuit are simultaneously employed.

My invention resides in further features and the method and apparatus of the character hereinafter described.

For an understanding of my method, and for an illustration of some of the various forms my apparatus may take, reference is to be had to the accompanying drawings, in which:

Fig. 1 is a diagrammatic view of radio receiving apparatus embodying my invention.

Fig. 1^a is a diagrammatic view of apparatus similar to that shown in Fig. 1, but utilizing a magnetic coupling in lieu of a capacitative coupling to the input circuit of the amplifier tube.

Fig. 2 is a diagrammatic view of radio receiving apparatus in general similar to that of Fig. 1, but utilizing in association with the coupling to the input circuit of the amplifying tube means for establishing a point of substantially zero potential with respect to the oscillations of undesired frequency.

Fig. 2^a is a fragmentary diagrammatic view of a modification of the arrangement of Fig. 2.

Fig. 3 is a diagrammatic view of apparatus in general similar to that shown in Fig. 1, but utilizing in the capacitative coupling to the input circuit of the amplifying tube inductance and capacity in parallel and resonant to the frequency of the undesired oscillations, and utilizing also a reverse magnetic coupling between the input and output circuits of the tube.

Fig. 4 is a diagrammatic view of a modification of my invention.

Referring to Fig. 1, A represents generally any absorption structure of a radio receiving system, either an open antenna path or, if desired, a closed circuit or loop, and broadly any circuit or path receiving energy directly from the natural media or more or less remotely coupled to such a circuit or path; and A may represent also a conductor system extending between transmitting and receiving stations as utilized, for example, in high frequency or carrier wave conductor systems. For brevity, however, my invention will be described in connection with radio receiving systems utilized for any purposes, such as control of movements of

ships or aircraft, of picture or motion picture apparatus, or signaling apparatus in general, including telegraphic and telephonic signals, it being understood that the translating instrument T, hereinafter referred to, represents generically any translating instrument, as a telephone or a control instrument of any character.

In the path between the antenna A and earth or counter-capacity E are included the variable tuning condenser C, which may be omitted if suitable or desirable, and the primaries P, P¹. The secondary S is oppositely inductively affected by the primaries P and P¹, whereby the circuit of the secondary S is not to any substantial degree affected by oscillations of any frequency simultaneously traversing the primaries P and P¹, when the switch s, in shunt to the primary P¹, is in open position indicated.

The secondary S is connected in the input or grid circuit of a thermionic tube V, which may be utilized either as the first stage of a series of radio frequency amplifiers, or, as indicated, as a detector. The tube V comprises the anode a, grid g and cathode or filament f. In series with the secondary S is the variable inductance or variometer L, both shunted by the tuning condenser C', and between a terminal of the latter and the grid g is included the usual grid condenser K shunted by the grid leak resistance r. In the anode circuit is the source of current B and the signal-translating instrument T, which may be a telephone or any other control instrument, or which may be the primary of the first of one or more stages of audio frequency amplification.

In shunt to the primary P¹ is the inductance L¹, with which is coupled the inductance L² connected with the source of current B in the anode circuit of the thermionic amplifier tube V¹, in whose grid or input circuit are included the inductance L³ and variable inductance or variometer L⁴, both shunted by the tuning condenser C². From a suitable point in the absorption circuit or path, represented by the antenna path A to E, and when the condenser C is present preferably from a point below said condenser, there is a coupling connection through the variable condenser C³ to a contact b movable along the inductance L³ for varying the degree of coupling between the input or grid circuit of the tube V¹ and the path from antenna through C², L³ to the earth or counter-capacity E. By preference this coupling is made loose or of small magnitude, and the smaller the better within operative limits, which relation, coupled with the preferred relation that the inductance greatly predominates over the condenser C³ in the input circuit, renders such input circuit highly selective, and it is made selec-

tive to the frequency of the desired oscillations, such as those representing the desired signal or control.

With the switch s in closed position, therefore, by in effect cutting out the inductances P^1 and L^1 , the antenna path is tuned, as by adjusting the condenser C , to the frequency of the desired oscillations representing the desired signal or control. And the circuit of the secondary S is similarly tuned by varying the inductance L or condenser C , or both, the inductance of the secondary S and of the instrument L preferably greatly predominating over the capacity C . The switch s is then opened, bringing into the antenna path the inductance L^1 in shunt to the primary P^1 , the magnitude of the inductance L^1 being preferably materially greater than, as twice or more, the magnitude of the inductance of the primary P^1 . Under these circumstances, due to the increased inductance in the antenna path, it is detuned with respect to the frequency of the desired oscillations or signal, and the frequency or predominant frequency of the oscillations set up in the antenna path by static, atmospheric or other electrical effects is lower than the frequency of the desired oscillations, and the decrement of the static or undesired oscillations is decreased because of the addition of inductance, and in consequence, oscillations of undesired frequency are more readily excluded from the circuit tuned to the frequency of the desired oscillations.

With the switch s open as aforesaid, both static and signal oscillations have substantially no effect upon the circuit of the secondary S because of its reverse couplings to the primaries P and P^1 , and there would be no effect upon the instrument T except for utilization of auxiliary means about to be described.

With the input circuit of the amplifying tube V^1 tuned to the frequency of the desired oscillations, oscillations of the desired signal or control are impressed upon such input circuit through the path C^3 , L^3 , E loosely coupled to the input circuit, the capacity of the condenser C^3 being adjusted to suitable magnitude for this purpose. In general, the magnitude of the capacity C^3 is made as small as suitable for operative purposes, when the oscillations due to static are of a frequency lower than the frequency of the desired oscillations, and under such circumstances the condenser C^3 effects a closer coupling for oscillations of desired frequency than for oscillations due to static or undesired frequency, the condenser C^3 in a broad sense selectively passing oscillations of desired frequency, and the loose coupling with the input circuit of the tube V^1 further assists in sharply excluding oscillations of undesired frequency from the input circuit.

Accordingly, the tube V^1 is affected substantially exclusively by oscillations of desired frequency, and these are amplified, in any suitable additional stages if desired, and the amplified oscillations traversing the inductance L^2 inductively influence the inductance L^1 , to which L^2 is preferably closely coupled, in such sense that the inductance of L^1 is in effect largely or materially reduced, whereby the inductance of L^1 and P^1 in parallel with each other is reduced, and therefore the natural period of the antenna path $A-E$ is changed in a sense approaching or equalling the period of the desired oscillations. Under these circumstances, the current in the primary P^1 is found to be small or substantially nil, and therefore the secondary S is influenced only by the primary P and only by oscillations of desired frequency, with the result that the signal-translating circuit now absorbs oscillations of desired frequency and translates them by means of the instrument T . The coil P^1 is preferably rotatable relative to the secondary S for balancing the effect upon the secondary S of the primary P . When the amplified oscillations are traversing the inductance L^2 , it is found that the primary P^1 may be rotated practically to any position with respect to the secondary S without producing any effect thereon, and this shows the substantial or complete absence of current in the primary P^1 when the inductance L^2 is traversed by amplified oscillations of the desired frequency.

Such portion of the static oscillations in the antenna path which traverses the inductance L^1 produces a slight or partial beat effect with the oscillations of signal frequency impressed upon inductance L^1 by inductance L^2 , but this causes a slight net effect by static oscillations upon the secondary S^2 , but this effect is of negligible magnitude. The oscillations of static frequency occurring in the inductance L^1 may influence the input circuit of the tube V^1 by the inductive influence of L^1 upon the output circuit of the tube V^1 , and through the capacity between the grid and anode of the tube V^1 , this capacity being represented in dotted lines at K^1 . The coupling effected between the output and input circuits by the capacity K^1 is neutralized by the coupling effected through the condenser C^3 , whereby any oscillations of static frequency influencing the input circuit of the tube V^1 through the condenser C^3 may be caused to neutralize the effect of static oscillations reaching the input circuit through the capacity K^1 from the inductance L^1 . This neutralization or balancing of couplings as regards the oscillations of static frequency may be determined with great nicety by suitable adjustment of the capacity of the condenser C^3 ; and this neutralization of

coupling is possible because of the aforesaid sense of coupling between the inductances L^2 and L^1 , to wit, such that the electro-motive-force across the terminals of the inductance L^1 due to oscillations of desired frequency in the antenna path is annulled by the electro-motive-force of the same frequency induced in L^1 by the oscillations of desired frequency in L^2 .

16 The coupling of the character effected by the condenser C^3 is preferably employed, but the system is to substantial degree operative without utilization of the condenser C^3 , presumably because of feed-back through the capacity K^1 of oscillations of signal frequency in the antenna path through the coupling L^1, L^2 to the input circuit of the tube V^1 .

17 Referring to Fig. 1^a, the coupling between the antenna path and the input circuit of the tube V^1 is effected magnetically by connecting in the antenna path the inductance L^5 loosely coupled to the inductance L^3 and in sense suitable for producing the effects described in connection with Fig. 1. It will therefore be understood that my invention comprehends both capacitative and magnetic coupling. Furthermore, it will be understood that the coupling L^5 may be omitted, and that the system is nevertheless to substantial extent operative without this coupling, as described above in connection with Fig. 1 as regards omission of the condenser C^3 .

18 In Fig. 2 the arrangement is in general similar to that of Fig. 1, except that the coupling condenser C^3 is connected to a point c at zero or substantially zero potential as regards the static oscillations or oscillations of undesired frequency. Such small or zero potential is effected by recourse to the coupling coil L^6 in the antenna path coupled to the inductance L^7 forming with the variable condenser C^4 a circuit tuned to the frequency of the undesired oscillations. One terminal of the condenser C^4 is connected to earth or counter-capacity E through the adjustable condenser C^5 , and the other terminal of the condenser C^4 is connected to the antenna path through the adjustable condenser C^6 . The condensers C^5 and C^6 effect a coupling of the circuit L^7, C^4 to the antenna path equal and opposite to that effected by the coils L^6 and L^7 , whereby the potential at the point c due to oscillations of undesired frequency is substantially nil. Nevertheless, oscillations of desired frequency, which are rejected by the circuit L^7, C^6 , influence the input circuit of the tube V^1 through the coupling comprising in this instance the two condensers C^6 and C^3 .

19 When the system is operated as described by maintaining substantially zero potential at the point c , static oscillations in the antenna path traversing the inductance L^1 may

to some extent influence the input circuit of the tube V^1 through its grid-anode capacity K^1 . To neutralize such coupling through the capacity K^1 , the input circuit is coupled to the output circuit, as by the inductance L^8 in the input circuit inductively related to the inductance L^2 , and in such sense that any electro-motive-forces produced in the input circuit through the capacity K^1 through the output circuit are neutralized by equal and opposite electro-motive-forces impressed upon the input circuit through the inductance L^8 .

20 The arrangement in Fig. 2^a is in general similar to that of Fig. 2, in that the potential at the point c is nil or substantially so regarding oscillations of undesired frequency. In this case the condenser C^3 between the point c and inductance L^3 is omitted, though it will be understood that it may be present. The condenser C^6 and its earth connection E of Fig. 2 are omitted in Fig. 2^a, and the point c is on the opposite side of condenser C^4 from that indicated in Fig. 2, the connection through inductance L^3 to earth E in this instance, whether or not a condenser C^3 be employed, completing the capacitative coupling path as effected by the condenser C^6 , and as before the coupling effected by the path including the condenser C^6 is equal and opposite to the coupling effected by the inductances L^6, L^7 .

21 In Fig. 3 there is included in the capacitative coupling path with the condenser C^3 the inductance L^9 in parallel with the condenser C^7 , forming a closed circuit resonant to the frequency of the undesired oscillations, and therefore offering in the coupling path a very high impedance to oscillations of that frequency, and so serving further to exclude oscillations of undesired frequency from the input circuit of the tube V^1 . By preference, the inductance L^9 preponderates over the capacity C^7 when the circuit C^7, L^9 is made resonant to the frequency of the undesired oscillations.

22 With the input circuit of the tube V^1 is preferably again associated the inductance L^8 coupled with the inductance L^2 for reasons generally similar to those described in connection with Fig. 2.

23 In Fig. 4 there is disclosed a system in general similar to those hereinbefore described. With the switch s closed, thereby short circuiting the inductance L^1 , and with switch s^1 open, the antenna path is tuned to the frequency of the desired or signal oscillations, and the circuit of the secondary S is tuned to the same frequency. Then upon closing the switch s^1 and opening the switch s , the inductance L^1 is brought into series in the antenna path, increasing its natural period, and the inductance L^{10} is then in parallel with the inductance L and primary P and is of a magnitude relatively

ly small compared with the sum of the inductances L^1 and P , whereby the larger part of the current of the oscillations of desired and undesired frequencies in the antenna path pass through inductance L^{10} , and the small current traversing the primary P is counteracted in its effect upon the secondary S by the relatively small primary P^1 , whereby the circuit of the secondary S is again practically free of energy of the oscillations of both desired and undesired frequencies. But by the action of the amplifier tube V and the coupling of its input circuit to the antenna path through the condenser C^3 , the action is in general similar to that hereinbefore described, and the signal-translating circuit including the secondary S absorbs energy of the oscillations of desired frequency to the exclusion of those of undesired frequency. When amplified oscillations of desired frequency traverse the inductance L^2 , the inductance L^1 is in effect reduced, causing greater amount of current to flow through the primary P and therefore disturb the balance and cause the signal-translating instrument to absorb energy of desired frequency.

Some of the features hereinbefore described and claimed are claimed in my prior Patent No. 1,521,777, January 6, 1925.

For the sake of brevity in the appended claims, the term "signal" is employed generically to include signals of any character, including telegraphic and telephonic signals, and any other analogous effect, including controls; and the term "static" is generally employed to include static and other natural electrical effects and also other effects having artificial origin such as are caused or represented by waves or oscillations other than those representing the desired signal or control.

What I claim is:

1. In the reception of radio signals, the method which comprises receiving the signal energy in a path having a natural period longer than the period of the received oscillations, and changing the natural period of said path by the effect upon the reactance thereof of oscillations produced by local energy.

2. In the reception of radio signals, the method which comprises receiving the signal energy in a path having a natural period longer than the period of the received oscillations, and decreasing the natural period of said path by the effect upon the reactance thereof of oscillations produced by local energy.

3. In the reception of radio signals, the method which comprises receiving the signal energy in a path having a natural period longer than the period of the received oscillations, amplifying the signal oscillations, and utilizing the amplified oscillations for

changing the reactance and thereby the natural period of said path.

4. In the reception of radio signals, the method which comprises receiving the signal energy in a path having a natural period longer than the period of the received oscillations, amplifying the signal oscillations, and utilizing the amplified oscillations for changing the reactance and thereby decreasing the natural period of said path to a magnitude substantially equal to the period of the signal oscillations.

5. The method of reducing the effect of static in the reception of signals, which comprises receiving the signal oscillations in a path having a natural period longer than the period of the signal oscillations, subjecting a second path tuned to the static oscillations in reverse senses to the static oscillations in said first named path for producing in said second path a point of substantially zero potential with respect to static oscillations, and transferring signal oscillations from said first named path to a third path tuned to the signal oscillations through said point of substantially zero potential.

6. The method of reducing the effect of static in the reception of signals, which comprises receiving the signal oscillations in a path having a natural period longer than the period of the signal oscillations, subjecting a second path tuned to the static oscillations in reverse senses to the static oscillations in said first named path for producing in said second path a point of substantially zero potential with respect to static oscillations, 100 transferring signal oscillations from said first named path to a third path tuned to the signal oscillations through said point of substantially zero potential, and utilizing local 105 energy in the form of oscillations for changing the natural period of said first named path.

7. The method of reducing the effect of static in the reception of signals, which comprises receiving the signal oscillations in a path having a natural period longer than the period of the signal oscillations, subjecting a second path tuned to the static oscillations in reverse senses to the static oscillations in said first named path for producing in said second path a point of substantially zero potential with respect to static oscillations, transferring signal oscillations from said first named path to a third path tuned to the signal oscillations through said point of substantially zero potential, amplifying signal oscillations, and utilizing the amplified oscillations for changing the natural period of said first named path.

8. In the reception of radio signals, the method which comprises receiving the signal energy in a path having a natural period longer than the period of the signal oscillations, influencing a signal-translating cir-

- cuit in opposite senses by the static and signal oscillations in said detuned path, whereby the effect upon said signal-translating circuit is substantially nil, and increasing the 5 absorption of signal energy from said path by the signal-translating circuit by influencing said path by oscillations produced by local energy to substantially tune said path to the frequency of the signal oscillations.
10. In the reception of radio signals, the method which comprises receiving the signal energy in a path detuned to the signal oscillations, subjecting a signal-translating path tuned to the signal oscillations in opposite 15 senses to magnetic influences of oscillations in said detuned path, and modifying one of said magnetic influences by oscillations of signal frequency.
11. In the reception of radio signals, the method which comprises receiving the signal energy in a path detuned to the signal oscillations, subjecting a signal-translating path in opposite senses to magnetic influences of oscillations in said detuned path, amplifying received signal oscillations, and modifying one of said magnetic influences by the 25 amplified oscillations.
12. A receiving system comprising a path traversed by signal and static oscillations 30 and having a natural period which is longer than the period of the signal oscillations, and means for changing the natural period of said path comprising means for changing the reactance of said path by local oscillations.
13. A receiving system comprising a path traversed by signal and static oscillations and having a natural period which is longer 35 than the period of the signal oscillations, and means for decreasing the natural period of said path comprising means for changing the reactance of said path by local oscillations.
14. A receiving system comprising a path traversed by signal and static oscillations and having a natural period which is longer 40 than the period of the signal oscillations, and means for amplifying oscillations of signal frequency, and means through which the amplified oscillations change the reactance of said path to change its natural period in a sense approaching the period of the signal-representing oscillations.
15. A receiving system comprising a path traversed by signal and static oscillations and having a natural period which is longer 45 than the period of the signal oscillations, and means for amplifying oscillations of signal frequency, and means through which the amplified oscillations change the reactance and thereby decrease the natural period of said path.
16. A receiving system comprising a path including inductances in parallel with each other and having a natural period longer than the period of the signal oscillations, and means for influencing one of said inductances by local oscillations to change the natural period of said path.
17. A receiving system comprising a path including inductances in parallel with each other and having a natural period longer than the period of the signal oscillations, means for amplifying oscillations of signal frequency, and means for influencing one of said inductances by the amplified oscillations for changing the natural period of said path.
18. A receiving system comprising a path including inductances in parallel with each other and having a natural period longer than the period of the signal oscillations, means for amplifying oscillations of signal frequency, and means for influencing one of said inductances by the amplified oscillations for decreasing the natural period of said path.
19. A receiving system comprising a path traversed by signal and static oscillations and having a natural period longer than the period of the signal oscillations, a circuit tuned to the static oscillations, means for coupling said circuit in reverse senses to said path for establishing a point of substantially zero potential with respect to the static oscillations, a second circuit tuned to the signal oscillations, and means for transferring signal oscillations to said second circuit through said point of zero potential.
20. A receiving system comprising a path traversed by signal and static oscillations and having a natural period longer than the period of the signal oscillations, a circuit tuned to the static oscillations, means for coupling said circuit in reverse senses to said path for establishing a point of substantially zero potential with respect to the static oscillations, a second circuit tuned to the signal oscillations, means for transferring signal oscillations to said second circuit through said point of zero potential, means for amplifying the signal oscillations in said second circuit, and means for decreasing the natural period of said path by the amplified oscillations.
21. A receiving system comprising a path traversed by signal and static oscillations and having a natural period longer than the period of the signal oscillations, a circuit tuned to the static oscillations, means for coupling said circuit in reverse senses to said path for establishing a point of substantially zero potential with respect to the static oscillations, a second circuit tuned to the signal oscillations, and means for influencing one of said inductances by the amplified oscillations for changing the natural period of said path.

oscillations, means for transferring signal oscillations to said second circuit through said point of zero potential, means for amplifying the signal oscillations in said second circuit, means for decreasing the natural period of said path by the amplified oscillations, a signal-translating circuit, and couplings between said circuit and said path for affecting said signal circuit in opposite senses to substantially equal extents.

22. A receiving system comprising a path traversed by signal and static oscillations and detuned with respect to the signal oscillations, a signal-translating circuit, couplings between said signal-translating circuit and said path for affecting said signal-translating circuit in equal and opposite senses, a thermionic amplifier having input and output circuits, means for impressing signal oscillations upon said input circuit, means for coupling said output circuit to said path for changing the natural period of said path by the amplified oscillations, and a coupling between said output and input circuits for neutralizing the effect upon said input circuit of static oscillations in said output circuit.

23. A receiving system comprising a path detuned to the signal oscillations and traversed by signal and static oscillations, transformer primaries in said path, a signal-translating circuit coupled in opposite senses to said primaries, an inductance in shunt to one of said primaries, and means for influencing said inductance by local oscillations for changing the natural period of said path.

24. A receiving system comprising a path detuned to the signal oscillations and traversed by signal and static oscillations, transformer primaries in said path, a signal-translating circuit coupled in opposite senses to said primaries, an inductance in shunt to one of said primaries, a thermionic amplifier having input and output circuits, means for impressing signal oscillations upon said input circuit, and means for coupling said output circuit to said inductance for influencing said inductance by amplified oscillations in such sense as to reduce the effect of said inductance upon the natural period of said path.

25. A receiving system comprising a path detuned to the signal oscillations and traversed by signal and static oscillations, transformer primaries in said path, a signal-translating circuit coupled in opposite senses to said primaries, an inductance in shunt to one of said primaries, a thermionic amplifier having input and output circuits, means for coupling said input circuit to said path, means for reducing static oscillations in said coupling, and means for coupling the output circuit to said inductance for varying by the amplified oscillations the effect of said inductance upon the natural period of said path.

inductance upon the natural period of said path.

26. A receiving system comprising a path traversed by signal and static oscillations and having a natural period longer than the period of the signal oscillations, a signal-translating circuit, couplings between said signal-translating circuit and said path for affecting said signal-translating circuit in equal and opposite senses, a thermionic amplifier having input and output circuits, means for impressing signal oscillations upon said input circuit, means for coupling said output circuit to said path for decreasing the natural period of said path by the amplified oscillations, and a coupling between said output and input circuits for neutralizing the effect upon said input circuit of static oscillations in said output circuit.

27. A receiving system comprising a path traversed by signal and static oscillations and having a natural period longer than the period of the signal oscillations, transformer primaries in said path, a signal-translating circuit coupled in opposite senses to said primaries, an inductance in shunt to one of said primaries, and means for influencing said inductance by local oscillations for decreasing the natural period of said path.

28. A receiving system comprising a path traversed by signal and static oscillations and having a natural period longer than the period of the signal oscillations, transformer primaries in said path, a signal-translating circuit coupled in opposite senses to said primaries, an inductance in shunt to one of said primaries, a thermionic amplifier having input and output circuits, means for impressing signal oscillations upon said input circuit, and means for coupling said output circuit to said inductance for influencing said inductance by amplified oscillations in such sense as to reduce the effect of said inductance upon the natural period of said path.

29. A receiving system comprising a path traversed by signal and static oscillations and having a natural period longer than the period of the signal oscillations, transformer primaries in said path, a signal-translating circuit coupled in opposite senses to said primaries, an inductance in shunt to one of said primaries, a thermionic amplifier having input and output circuits, means for coupling said input circuit to said path, means for reducing static oscillations in said coupling, and means for coupling the output circuit to said inductance for varying by the amplified oscillations the effect of said inductance upon the natural period of said path.

30. A receiving system comprising a path detuned with respect to the signal oscilla-

tions and traversed by signal and static oscillations, a signal-translating circuit, means for coupling said circuit in opposite senses to said path, an inductance in said path, a thermionic amplifier having input and output circuits, said output circuit coupled to said inductance, a coupling connection between said path and said input cir-

cuit, a coupling condenser in said connection, and an inductance and capacity in parallel with each other and in series in said coupling connection, said last named inductance and capacity forming a circuit tuned to the frequency of the static oscillations. ¹⁰

DAVID G. McCAA.
